His. ATTORNEY.

UNITED STATES PATENT OFFICE.

HOWARD PARKER, OF BERLIN, NEW HAMPSHIRE, ASSIGNOR TO BROWN COMPANY,
OF BERLIN, NEW HAMPSHIRE, A CORPORATION OF NEW HAMPSHIRE.

PIPE WRENCH.

1,422,303.

Specification of Letters Patent. Patented July 11, 1922.

Application filed July 31, 1920. Serial No. 400,396.

To all whom it may concern:

Be it known that I, HOWARD PARKER, a citizen of the United States, and a resident of Berlin, county of Coos, State of New Hampshire, have invented certain new and useful Improvements in a Pipe Wrench, of which the following is a specification.

The object of this invention is to provide a pipe wrench having features of novelty and advantage. It is of particular advantage in that it may be used on a pipe without danger of mutilating, marking, crushing or otherwise damaging the same. The device of the present invention is peculiarly adapted for use in connection with pipes formed of paper pulp and the like although, of course, it is applicable to pipes of other kinds.

In the accompanying drawings wherein one embodiment which the wrench of the present invention may take is shown—

Fig. 1 is the side view and

Fig. 2 is a top or edge view.

Referring to the drawings in detail, *a* denotes a handle to the forward end of which is connected, by means of links *b* and a spring *c*, a strap *d* adapted to be passed about a pipe *p* shown in dotted lines in the drawing.

The handle has at its forward end a curved edge 10 forming a gripping surface or jaw. The links *b* are pivotally connected to the handle by the pin 11 and to the outer ends of the links is connected, by means of a pin 12, a spring *c* which, as shown, may be in the form of a split band ring of considerable stiffness. Connected to the other end of the spring is a shackle 13 through which passes the strap *d*. The strap *d* may be doubled back upon itself as shown, the bend receiving the shackle 13 and the free end of the strap passing between the jaw 10 and that end of the spring *c* connected to the links *b*. This end of the spring may be said to constitute a jaw 14 complementary to the jaw 10. 15 is a roller journaled on the pin connecting the shackle 13 to the spring.

The operation of the wrench will be readily understood. The strap *d* is passed about the pipe *p* and is drawn thereagainst by pulling the free end of the strap out towards the end of the handle, the handle being raised slightly from the position shown in

Fig. 1 so that the strap is not pinched between the jaws 10 and 14.

To turn the pipe *p*, the handle *a* is swung downwardly whereupon the strap is tightly gripped between the complementary jaws 10 and 14 and the forward end of the handle will take up slack in the strap *d*. In the event such force is applied to the handle as might crush the pipe or strip the threads thereon when the pipe is being screwed into another pipe, the spring will be distended sufficiently to permit the strap *d* to slip about the pipe and thus injury to the latter is prevented. After the spring is distended to the extent that the roller 15 and the tip 16 of the forward end of the handle are brought opposite each other, the handle will pivot about its tip without increasing the grip of the strap about the pipe.

It is, of course, obvious that my invention is susceptible of various modifications and changes which are within the spirit of the invention without departing from the scope of the following claims, it being understood that the present disclosure of my invention is by way of illustration only and it is not to be taken as restrictive of my conception.

I claim as my invention:

1. A pipe wrench including a handle and a flexible band secured at one end and detachably connected at its other end to said handle, said band having an effective gripping action throughout its engagement with the pipe and including extensible means permitting of extension of said band to prevent injury to the pipe when the force applied is excessive.

2. A pipe wrench including a handle, a flexible band secured at one end and detachably connected at its other end to said handle and adapted to grip the pipe throughout its engagement therewith when the handle is turned, said band including a resilient spring.

3. A pipe wrench including a handle having a fixed jaw, a complementary jaw pivoted to the handle, and a flexible band secured to said pivoted jaw and passing between said jaws so as to be gripped thereby, said band including a resilient spring.

4. A pipe wrench including a handle provided with a fixed jaw, a pair of links pivoted to the handle one on each side thereof, a split resilient ring one end of which is con-

nected between the free ends of said links and constitutes a jaw complementary to said fixed jaw, and a flexible strap connected to the other end of said ring and having one end passing between and gripped by said jaws.

5. A pipe wrench including a handle and a band connected to said handle and having an effective gripping action throughout its

engagement with the pipe when the handle is turned, said band including resilient means permitting of automatic expansion of said band and slippage thereof about the pipe when the force applied is excessive.

HOWARD PARKER.
